MOLDED PULP CELLULAR CONTAINER

Thomas B. Kennedy, Stamford, Conn., and Henry A. Lord, Palmer, Mass., assignors to Diamond International Corporation, New York, N.Y., a corporation of Delaware

Filed May 6, 1965, Ser. No. 85,136

Term of patent 14 years

(Cl. D58—13)

FIG. 2

FIG. 3

FIG. 4

FIG. 5

FIG. 6

FIG. 7

FIG. 1 is a top plan view of a molded pulp cellular container showing our new design.

FIG. 2 is a bottom plan view;

FIG. 3 is a side elevation;

FIG. 4 is a vertical section on an enlarged scale taken through line 4-4 of FIG. 1 and looking in the direction of the arrows;

FIG. 5 is a vertical section on an enlarged scale taken through line 5-5 of FIG. 1 and looking in the direction of the arrows;

FIG. 6 is a vertical section on an enlarged scale taken through line 6-6 of FIG. 1 and looking in the direction of the arrows; and

FIG. 7 is a fragmentary bottom view in perspective on an enlarged scale.

We claim:

The ornamental design for a molded pulp cellular container, as shown.
